TALLY MECHANISM FOR KNITTING MACHINES

Charles W. Strzaikowski, Milwaukee, Wis.

Application December 22, 1937, Serial No. 181,119

5 Claims. (Cl. 66—33)

My invention relates to improvements in tally mechanisms for knitting machines.

My object is to provide a knitting machine with combined automatic and manually operable indicators, which may be conjointly used to indicate the operating efficiency of a flat knitting machine.

More particularly, my object is to provide a knitting machine with means for automatically keeping plural course records, one of which operates continuously and is not subject to control by the operator, whereas another one is subject to control by the operator for re-setting purposes; to provide associated mechanism for automatically advancing a record sheet step by step upon completion of any given operation for production of any given set of blanks; to provide a housing for said record sheet, with a slot through which the operator may have access to the portion of the sheet representing the production of any given set of blanks, whereby the operator may apply index characters to the record sheet to indicate defects appearing in one or more of the blanks or any other difficulty requiring a temporary stoppage of the machine; and to so connect such mechanisms with the movable parts of the knitting machine as to provide for their cooperation in the production of a correct operating record, which may serve as a basis to verify or dispute an operator's statement, and indisputably show the operating efficiency of the machine for any desired period of time.

A further object is to provide a flat knitting machine with a course counter and a cooperative product counter.

In the drawings:

Figure 1 is an elevation of my improved tally mechanism and the associated portions of a flat knitting machine.

40 Figures 2 and 3 are sectional views, drawn, respectively, to lines 2—2 and 3—3 of Figure 1.

Figure 4 is a plan view of the counting wheel cabinet, with the top portion of the cabinet removed.

45 Figure 5 is a sectional view drawn generally to line 5—5 of Figure 4.

Figure 6 is a sectional view of the record sheet holder and its cabinet, drawn generally to line 6—6 of Figure 7.

50 Figure 7 is a sectional view drawn to line 7—7 of Figure 6.

Figure 8 is a developed view of the index chart.

55 Figure 9 is a detail view of the index chart as it appears when wound on its supporting core.

Like parts are identified by the same reference characters throughout the several views.

The flat knitting machine to which my invention is applied may be assumed to be of ordinary type, adapted for the simultaneous knitting of a 5 series of stocking blanks.

Flat knitting machines made in multiple sections are in common use. Machines designed to knit as high as two dozen stocking blanks in one operation are frequently employed, and whenever 10 a thread supplying one of the sections is broken or the knitting operation otherwise interrupted, the operator must shut down the entire machine long enough to make the necessary adjustments to prevent further feeding of thread to that section. Therefore, it is important to keep a record 15 of the total number of courses knitted and of the interruptions of its operation during any given day and of the sections responsible for such interruptions, whereby a superintendent or 20 other officer may receive information as to the total time loss and the total number of imperfect blanks knitted.

Flat knitting machines are ordinarily provided with control chains 10, (Figures 1 and 2), which 25 are made up of detachable links. Each link represents one knitted course, and one of these links is provided with a lug or cam projection 11 to automatically stop the machine when the required number of courses have been knitted to 30 complete a given set of blanks. Pattern cam projections 12, offset on the chain from the projection 11 (Figure 2), may be employed to stop the machine at those stages of the knitting operation which require the addition or subtraction 35 of operating needles to enlarge or reduce the width of the blank after a given number of courses have been knitted. The machine stopping levers or members which these cams operate are in common use and need no description, as they are 40 not a part of the invention herein described.

For the purposes of my invention, I utilize a similar cam projection to operate a suitable counter once during each cycle of chain travel. In the construction illustrated, the chain 10 45 travels in the direction indicated by the arrow in Figure 1, and the cam projection 11 is in a position to actuate a striker finger 14 (Figure 1), and thereby oscillate a pivoted lever or dog 15 50 to transmit motion through the link rod 16 to a crank arm 17 which operates a counter mounted in a cabinet 18 supported from the frame of the machine. Preferably the counter will be thus operated immediately prior to contact of the pro- 55

jection 11 with the machine stopping striker 19 (Figure 1).

As shown in Figures 6 and 7, the crank arm 17 is connected with an oscillatory shaft 20 journaled in the cabinet 18 and provided with an interior crank arm 21, which transmits motion step by step to a counting carrier such as the drum 22, through the link 23, lever 24, dog 25, and ratchet wheel 26, the latter being fixedly connected with the hub of the drum 22, whereas the lever 25 is mounted to oscillate on said hub.

A tension spring 28 connects link 23 with one wall of the cabinet, as best shown in Figure 7, and this spring tends to retract the motion transmitting connections and the dog 25 after each step movement of the ratchet wheel 26. An auxiliary spring 29 connects the lever 16 with the frame and tends to hold the finger 14 in a normal position, with the motion transmitting end 20 of the lever in contact with a suitable stop 30.

By employing two springs 28 and 29, it is possible to use a wire or any other flexible link 16, whereas if only one spring were employed, the link 16 would be required to transmit motion in both directions.

The drum 22 is formed to receive a cylindrical core 35 around which a record sheet or strip 36 may be wound and secured by any suitable means. Where the length of the chart corresponds with the circumference of the core, it may be wound upon the core and secured thereto by rubber bands 37. Otherwise the chart may be secured to the core at only one end and wound upon the core while the record is being made.

Each chart is preferably sub-divided by numbered longitudinally and transversely extending lines, as shown in Figures 8 and 9. The spaces between the longitudinally extending lines are numbered in correspondence with the number of sections in the knitting machine, and those between the transversely extending lines are numbered in correspondence with the blanks to be knitted within a day or other period of time represented by the chart. Therefore, as the drum 22 revolves step by step spaces representing each blank to be knitted will be exposed through a slot 40 in the top of the cabinet, whereby, whenever a defect appears in the blank which is being knitted in any section of the machine, the operator can stop the machine and can indicate the nature of the defect in the proper square on the chart, thereby indicating the section in which the defect occurred.

When the machine is again set in operation, this record is moved out of registry with the slot 40 as soon as the blanks of that particular set have been completed. Each chart will carry an index of symbols to be used by the operator to indicate the particular character of defect for which the machine was stopped.

The cabinet is provided with a door 42 which may be locked by the superintendent or other officer, and opened only for the removal of the cores 35 to permit removal and substitution of charts 36. After replacement of a chart, the core is replaced on the drum 22. The inner end of the drum will preferably be made conical as indicated at 43, whereby, when the core is pushed into place, it will be held to the drum and rotated therewith. However, the particular means for securing the core to the drum is not material to the invention herein claimed beyond the requirement that it be sufficient to cause a step by step movement of the core and chart with the movements of the drum.

If desired, auxiliary course counters may be employed. In the machine illustrated, the shaft 50 makes one complete revolution for each course knitted, and motion may be transmitted from this shaft to counting mechanism contained within the cabinet 51, whereby each revolution of the shaft and each corresponding course knitted by the machine in each of the several sections may be registered. In Figure 4 I have illustrated at 54 an ordinary counting mechanism, provided with a series of counting wheels driven by an oscillatory shaft 55, to which motion is communicated from the shaft 50 through the eccentric 56 (Figure 1), link 57, crank 58, shaft 59 (Figure 4), crank 60, connecting rod 61, and a crank 62 on shaft 55. As indicated in Figure 1, the cabinet 51 normally encloses the counter 54 so that it is not subject to control by the operator of the machine. It furnishes a correct record of the number of revolutions of the shaft 59 under normal knitting conditions.

An auxiliary counter 67 may be driven from the same connecting rod 61 through a crank 68 and the driving shaft 69 of the counter. This counter 67 may be re-set to a starting point or zero point by means of the re-setting rod 70 and exterior manually operable knob 71.

As is usual in such counters, the operating crank 68 will be swung by the driving mechanism in one direction and retracted by a spring 72 or equivalent means, whereas the re-setting rod 70 may be operated in the opposite direction to restore the counting wheels to the starting point without actuating the crank 68.

The operation of my improved tally mechanism 35 will be understood from the foregoing description, but may be briefly reviewed as follows.

A complete record of the number of blanks knitted and of defects appearing in each set of blanks will be produced on the charts 36, each of which will be used for a given period and then replaced by another chart. This record will be automatically produced, with the exception of the symbols which identify the character of the defect and the particular blank in which it appears. The operator of the machine cannot change these symbols after completion of any given set of blanks for the reason that the record for that set of blanks moves out of reach by the operator immediately prior to the completion of those blanks.

The record produced by the blanks 36 may be checked against the record of courses knitted, which is automatically maintained by the tally 54, thereby enabling the superintendent, 55 inspector, or other official to ascertain by comparison of the two records when the operation of the machine has been unduly delayed during any given period of time represented by one of the charts 36.

The auxiliary tally 67 is entirely under the control of the operator through the knob 71. The purpose of this tally is to keep a record of the courses knitted during the production of one set of blanks, whereby whenever the machine is stopped by one of the cam projections 12 (Figure 2), the operator may inspect the tally and thereby ascertain the nature of the adjustment to be made at that stage of operation. By resetting this tally upon completion of each set of blanks 70 the operator may be kept informed as to all required re-adjustments of the needles by instant ascertainment of the knitting stage at which the machine has been automatically stopped.

While I have described the counter in cab- 75

inet 18 as being actuated step by step once during the manufacture of each set of blanks, it is not material to my invention whether this counter is operated once or more than once, the number of operations being dependent upon the number of projections 11 on the pattern chain. For example, the projections 11 might operate this counter upon completion of each one hundred courses knitted by the machine.

5 10 I claim:

1. The combination with a flat knitting machine having multiple sections for the simultaneous knitting of separate blanks, of means for recording defects appearing in any of said blanks, 15 said recording means being adapted to indicate the sections of the machine in which the defect occurs, and means driven by said machine at predetermined intervals for advancing the recording means step by step beyond the control 20 of the operator.

2. The combination with a flat knitting machine having multiple sections for the simultaneous production of knitted blanks, of a counter for registering the number of blanks knitted, 25 and means associated with the counter for maintaining a record of defects appearing in the

blanks and the sections of the machine in which the defective blanks are produced.

3. The combination with a flat knitting machine provided with a control chain having a machine stopping member, and a counter operatively connected with said chain for periodic operation, and provided with means for manually recording the character of defects requiring a stoppage of the machine.

4. The combination with a flat knitting machine provided with a machine driven control chain having a machine stopping member, and a counter operatively connected with said chain for periodic operation, said counter being provided with means for recording defects in each 15 knitted blank produced by said machine.

5. The combination with a flat knitting machine, of a counter uncontrollable by the operator, an auxiliary counter provided with accessible resetting means, and a product counter 20 adapted to register the number of blanks produced in a given period of time, each of said counters being operatively connected with motion transmitting portions of said machine.
